UNITED STATES PATENT OFFICE.

WILLIAM KERNOCHAN, OF BROOKLYN, NEW YORK.

CARPET-FASTENER.

No. 820,502.

Specification of Letters Patent.

Patented May 15, 1906.

Application filed January 19, 1906. Serial No. 296,768.

To all whom it may concern:

Be it known that I, WILLIAM KERNOCHAN, a citizen of the United States, residing at Brooklyn, in the county of Kings and State 5 of New York, have invented certain new and useful Improvements in Carpet-Fasteners, of which the following is a specification, such as will enable those skilled in the art to which it appertains to make and use the same.

This invention relates to means for securing carpet to a floor or a pair of stairs; and the object thereof is to provide an improved device or devices for this purpose which may be conveniently used for securing a carpet, 15 linoleum, or any other floor or stair-covering to a floor or to a pair of stairs or to any support to which it is desired to secure a carpet or other flexible covering.

The invention is fully disclosed in the following specification, of which the accompanying drawing forms a part, in which the separate parts of my improvement are designated by suitable reference characters, said drawing being a view showing a part of a 25 flooring in section and showing a piece of carpet or other covering material placed thereon and my improved means for securing the carpet or covering material to the floor.

In the drawing forming a part of this 30 specification I have shown at *a* a flooring, and at *b* a piece of carpet, linoleum, or other floor-covering material, and in the practice of my invention I provide a short tube *c*, which is secured in the flooring or passed 35 therethrough and secured therein, and in connection with the tube *c* I employ a tubular pin *d*, having a head *d*² and a pointed end *d*³. Secured in the pin *d* is a spring *e*, which ranges longitudinally thereof, and one end of 40 which is secured in the head of the pin *d* at *e*², and the other end of which is provided with a hook member *e*³, which passes out through a corresponding hole in the side of the tubular pin *d* at *e*⁴.

In practice the tube *c* is secured in the 45 floor, and the carpet or other floor-covering is placed thereover, and the pin *d* is passed

downwardly through the carpet or other floor-covering into and through the tube *c*. In this operation an awl or similar device 50 comprising a handle *f*, having a pin or shank member *f*², is forced into the tubular pin *d*, as clearly shown in the drawing, and this operation forces backwardly the hook member *e*³ of the spring *e*, and the pin with the awl there- 55 in is forced downwardly through the carpet and through the tube *c*, after which the awl is withdrawn and the hook member *e*³ of the spring *e* springs outwardly, as shown at the left of Fig. 1, and the pin *d* is locked in the 60 tube *c*, the hook member *e*³ of the spring *e* engaging the lower end of the said tube.

This device, as will be understood, may be used for securing ordinary carpets to floors, 65 stair-carpets to stairs, or linoleum or any other floor-covering material to floors or to stairs and may also be used for analogous purposes in other relations.

Having fully described my invention, what I claim as new, and desire to secure by Letters Patent, is—

The herein-described means for securing carpets and other material to floors, stairs and the like, comprising a tube adapted to be secured in the floor or stairs, a hollow pin 75 adapted to be passed through the carpet or other material and through said tube and provided at one end with a head and at the other end with a point, said pin being also provided near the pointed end with a hole in 80 one side thereof, and a spring secured in said pin and provided with a hook which normally projects outwardly through said hole, said hook being adapted to be forced inwardly by a device inserted into said pin, 85 substantially as shown and described.

In testimony that I claim the foregoing as my invention I have signed my name, in presence of the subscribing witnesses, this 18th day of January, 1906.

WILLIAM KERNOCHAN.
